UNITED STATES PATENT OFFICE.

THOMAS HIGGINSON STRINGER AND WILLIAM HENRY STRINGER, OF LEICESTER, ENGLAND.

MACHINE FOR ATTACHING BUTTONS, BUCKLES, AND LIKE ORNAMENTS TO BOOTS, SHOES, GAITERS, AND KINDRED ARTICLES.

No. 921,306.

Specification of Letters Patent.

Patented May 11, 1909.

Application filed November 29, 1907. Serial No. 404,205.

To all whom it may concern:

Be it known that we, THOMAS HIGGINSON STRINGER and WILLIAM HENRY STRINGER, sewing-machinists, subjects of the King of Great Britain and Ireland, residing at Leicester, in the county of Leicester, England, have invented a new and useful Machine for Attaching Buttons, Buckles, or Like Ornaments to Boots, Shoes, Gaiters, and Kindred Articles, of which the following is a specification.

This invention relates to that type of machine wherein a wire staple is formed, driven home, and clenched, and consists in a novel arrangement and combination of parts whereby, while one staple is being driven into the work, the next one is in process of formation, so enabling the above enumerated operations to be performed in a continuous and more expeditious manner than heretofore.

According to this invention, wire-feed mechanism is operated simultaneously with a reciprocating plunger formed with a cutter, a staple former, and a tongue, in such a manner that, during the down stroke of the said plunger, a length of wire is fed beneath the cutter, is severed, and is then formed into a staple upon a swage, while the staple formed by the previous down stroke is forced into the work; the staple formed during the down stroke of the plunger is, during the return stroke, pushed off the swage and into the path of said tongue where it is supported upon a spring-controlled lever until the succeeding down stroke of the plunger, whereupon it is forced into the work. And in order that the invention may be readily understood, we will now describe it fully with reference to the accompanying drawings, wherein:

Figure 1 is a front elevation of a machine embodying our improvements, and designed to be operated by any suitable treadle arrangement, and Fig. 2 is a side elevation thereof. Fig. 3 is a detached view in vertical section, and to a larger scale than the previous figures, of the die-box showing the plunger about to cut off a length of wire. Fig. 4 is an elevation at right angles to Fig. 3, 50 showing the interior of the die-box. Fig. 5 is a view similar to Fig. 4, but showing the plunger and die-box in the position for clenching the staple. Fig. 6 is likewise a view similar to Fig. 3, but showing the 55 plunger in its uppermost position and the

staple formed by the previous stroke supported in its groove. Fig. 7 illustrates the means for removing the staple from the swage upon which it has been formed. Fig. 8 is a plan of the arm on which the work is supported, and carrying the die on which the staple is clenched.

The plunger *a* is detachably connected to a rod *b*, which is supported, by means of a collar *b*¹, upon a spring *b*², disposed between the head *c* of the standard *c*¹, and a guide *c*². The rod *b* passes up through the head *c*, while the lower extremity of the plunger *a* passes into the die box *d* working in the guide *c*² formed upon the front of the standard *c*¹. This die-box, as will be hereinafter explained, has a permissive vertical movement to give clearance for placing the work between it and the clenching die *c*¹.

The plunger *a* is formed with a cutter *a*¹, a groove *a*² for forming the staple, and a tongue *a*³, for driving the formed staple into the work. The back of the die-box *d* is formed with a groove *d*¹, for the reception of a stop *a*⁴, provided at the back of the plunger *a* for limiting the upward travel of the latter, and this box is furnished with a swage *d*² on which the staple *i* is formed, and with an arm *f*, the lower end of which is bifurcated to pass on each side of said swage, while the opposite end of this arm is pivotally mounted within the groove *d*¹. At the rear of the arm *f*, is a spring-controlled plunger *f*¹, housed within a block *g* attached to the die-box *d*, and this spring normally maintains the bifurcated end of the arm *f* in its forward position. Upon the front of the die-box is a cover plate *d*³ formed with a lateral arm *d*⁴, and a plate *d*⁵, whereon is mounted a bent lever. The arm *h* of this lever extends into a channel *d*⁶, as hereinafter described, in the die-box, where it supports the staple *i*, while the other arm *h*^x of said lever is pivotally mounted in the cover plate *d*⁵. A spring *h*¹ is provided for normally maintaining the arm *h* in the channel. The lateral arm *d*⁴ projects through a slot *d*^x in the cover-plate *c*² of the guide *c*; this arm on the downward stroke of the plunger, contacting with an adjustable stop *e* which regulates the permissive movement of the die-box.

In order to prevent the channel *d*⁶ becoming choked by a twisted or imperfectly formed staple, in case the treadle should not have been fully depressed by the operative,

means are provided at the lower end of the die-box, and are adapted to be readily operated by the plunger and said staple, and which means, on separating, bring about the 5 enlargement in width of the channel and thereby the ready ejection of the imperfect staple. These means advantageously consist of two plates d^7 pivotally mounted at d^8 on each side of the die-box and extending 10 outwardly on each side thereof; and said plates being positioned between the cover-plate d^5 and the back of the die-box d . The inner ends of each of these plates is rabbeted, so that when the plates are in their normal 15 position, that is to say when they abut one against the other, the rabbets constitute the hereinbefore mentioned channel d^6 ; and to maintain the plates in contact and preserve the normal width of channel, a spring d^9 , 20 secured to the underside of the block g , is provided, and is adapted to bear against the outer and upper ends of the plates d^7 . If, therefore, the staple should become twisted or imperfectly formed, and prevent the 25 regular working of the machine, the tongue a^3 of the plunger a , when descending, will cause the said staple to force apart the plates, so increasing the width of the channel, and will then permit such staple to fall out of 30 the machine, and the working thereof to be at once resumed. The plates d^7 are then restored to position by the spring d^9 .

The wire i^1 , for forming the staple, is led from a conveniently disposed spool (not 35 shown), and passes through a hole i^2 in the die-box; it is fed into this box by means of mechanism constructed as follows:—Upon an arm g^1 , formed on the block g , is mounted, in a bearing g^2 , a hollow shaft j , to one end of 40 which is attached a roller j^1 formed, or provided, with a toothed wheel j^2 , while on the other end of said shaft is mounted a ratchet j^3 . Passing through the hollow shaft j is an axis k , on which is mounted a disk k^1 furnished with a spring pawl k^2 adapted to engage with the ratchet j^3 . Pivotally mounted 45 upon the block g , is another arm l carrying an axis l^1 on which is rotatably mounted another roller l^2 formed, or provided, with a toothed wheel l^3 . The arm l is connected to 50 the arm g^1 , by means of a stud l^4 which is furnished with a coiled spring l^5 , so arranged as to maintain a yielding contact between the two rollers j^1 and l^2 , while their respective toothed wheels j^2 and l^3 are held in gear. The wire i^1 , on its way from the spool, passes 55 between the rollers j^1 , l^2 , and thence, by way of a tubular guide g^3 , to the hole i^2 in the die-box, and across said die-box until it abuts 60 against the opposite side of the same. To operate the rollers j^1 , l^2 , a cam m is provided, and is formed on a plunger m^1 working in a guide m^2 , in the standard c^1 . Engaging with the cam m is a spring-controlled forked arm 65 m^3 , pivotally mounted upon the foot of the

machine, the fork receiving a stud m^4 extending from the rear of the disk k^1 , and said stud serves to rotate the disk. The plunger m^1 is arranged at the rear of the rod b in such a manner that a lever n , pivotally mounted 70 in the head of the standard, engages both the rod and the plunger, so that upon vibrating this lever, which may be effected by connecting it, by means of a rod n^1 , to a treadle (not shown) the plunger and the rod are reciprocated simultaneously. 75

The standard is formed with a curved arm c^3 , on which the work is supported, and this arm is furnished with a die-plate c^4 upon the face of which are formed two notches c^5 80 which turn the points of the staple i up into the work.

The working of the machine is as follows: On the lever n being depressed, the rod b and plunger m^1 are forced down, and in their descent the plunger m^1 operates the wire feed-mechanism so causing it to feed a length of wire into the die-box d . Simultaneously with this feeding, the cutter a^1 , of the plunger a , has descended to the hole i^2 in the die-box 90 (as shown in Figs. 3 and 4) and has severed the wire, the detached piece of which is thereupon brought by the cutter to the swage d^2 . The plunger continuing to descend bends the wire over the swage by the groove a^2 in 95 said plunger, and the staple i is thereupon formed, (as shown in Fig. 5). During this operation, that is to say the forming of the staple, the tongue a^3 of the plunger will have passed into the channel d^6 and engaged with 100 the staple formed by the previous down stroke, this staple having, meanwhile, been supported (as shown in Fig. 6), upon the arm h of the bent lever. The last mentioned staple is now forced by the plunger through the 105 channel d^6 , and when said plunger has descended to its lowermost position in the die-box, it, together with [said die-box, will be forced down upon the work until the arm d^4 on the die-box, contacts with the stop e on 110 the cover plate of the guide c^2 . While forcing the staple through the work, the points of the former will be turned inward by the grooves c^6 in the die-plate c^4 , with the effect that the staple will be clenched in the work. 115

The lever n now rises, releasing the spring b^2 , which latter then forces up the plunger a . The pivotally mounted arm f which, during the descent of the plunger and the formation of the staple, had been forced back, will now 120 be pushed forward by its spring-plunger f^1 , whereupon the staple which had been formed upon the swage d^2 , will be pushed into the channel d^6 , and will fall upon the arm h of the bent lever, ready for the next down stroke 125 of the plunger, and so on continuously.

Having now described our invention, what we claim and desire to secure by Letters Patent, is:

In a machine for securing buttons, buckles, 130

or like ornaments to boots, shoes, gaiters, and kindred articles, the combination with a reciprocable plunger furnished with a wire cutter, a staple former, and a tongue or driver, 5 of a reciprocating die-box wherein a staple is formed, wire feed-mechanism attached to said die-box, a plunger for operating said wire feed-mechanism, and two spring-controlled rabbeted plates pivotally mounted 10 upon the lower end of said die-box to form

an adjustable outlet channel for permitting the passage of a malformed staple.

In witness whereof, we have hereunto signed our names in the presence of two subscribing witnesses.

THOMAS HIGGINSON STRINGER.

WILLIAM HENRY STRINGER.
